UNITED STATES PATENT OFFICE.

CLAUDE MILTON EARLEY, OF BROOKLYN, NEW YORK.

CUTTING MACHINE FOR PRINTING-PRESS ROLLERS.

Application filed December 29, 1923. Serial No. 683,481.

To all whom it may concern:

Be it known that I, CLAUDE M. EARLEY, a citizen of the United States, and a resident of the city of New York, borough of Brooklyn, in the county of Kings and State of New York, have invented a new and Improved Cutting Machine for Printing-Press Rollers, of which the following is a full, clear, and exact description.

10 This invention relates to a machine which is particularly designed for cutting and trimming printing press rollers.

In the art of printing, it is necessary to divide the roller surface into longitudinally spaced sections when running through multi-colored work, and this is accomplished by cutting a number of circumferential grooves to produce the required number of divisions. The printing rollers which are of an extremely tough composition, usually glycerine and glue, are at the present time almost universally cut by hand with a knife for producing the grooves, as well as for trimming the ends. This practice, in addition to entailing a considerable amount of time and labor, leaves a rough finish to the groove which precludes the proper cleansing of the same and very often results in the mutilation of the smooth operating surface when running in the press.

It is, therefore, the outstanding object of the present invention to overcome the above recited objectionable features and disadvantages by providing a machine which operates to simultaneously trim the ends of the rollers and to circumferentially groove the same for dividing the surface thereof into the required number of divisions.

As a further object the invention contemplates a machine of the character set forth, which will produce a clean cut groove, leaving the surfaces smooth, even and uniform, whereby to eliminate any possibility of mutilation while running, and to permit of the washing and cleansing of the cut portions with the same facility as the washing of the roller surfaces.

The invention contemplates as a still further object the provision of a machine of the character set forth which may be employed for the cutting of a helical or spiral groove in the surface of a feed roller where it is expedient to reduce the amount of ink to be fed from the fountain. By this method a more uniform feeding of the color can be accomplished than under the present prac-

tice, in which the press man is required to intermittently lift the fountain pawl when an over-supply of color accumulates. In this connection a still more important feature is 60 the fact that a greater flow of ink can be carried by the ductor roller of the fountain, thus precluding the necessity of tightening up the fountain blade which oftentimes results in the cutting of the ductor roller of the 65 fountain or springing of the fountain blade.

The invention furthermore comprehends a machine of the character set forth which is comparatively simple in its construction and mode of operation, which is thoroughly 70 reliable and highly efficient in its purpose, and which is inexpensive to manufacture and produce.

With the above recited and other objects in view, the invention resides in the novel 75 construction set forth in the following specified claims and illustrated in the accompanying drawings, it being understood that the right is reserved to embodiments other 80 than those actually illustrated herein to the full extent indicated by the general meaning of the terms in which the claims are expressed.

In the drawings—

Figure 1 is a front view of a machine constructed in accordance with the invention.

Fig. 2 is a plan view thereof.

Fig. 3 is a cross sectional view there-through taken approximately on the line indicated at 3—3 in Fig. 2.

Fig. 4 is a perspective view of one of the cutting or trimming tools removed from the machine.

Fig. 5 is a fragmentary enlarged sectional 95 view taken approximately on the line 5—5 of Fig. 3.

Fig. 6 is a fragmentary enlarged sectional view taken approximately on the line indicated at 6—6 in Fig. 2.

Fig. 7 is a fragmentary enlarged sectional view taken approximately on the line 7—7 of Fig. 6.

Fig. 8 is an enlarged detail sectional view 105 taken approximately on the line 8—8 of Fig. 2.

Fig. 9 is a diagrammatic view illustrating a circuit including one of the cutting tools.

Referring to the drawings by characters of reference, the machine includes a supporting framework 10 which consists of vertical legs 11 connected by upper and lower longi-

tudinal rails 12 and 13 and upper and lower cross rails 14 and 15, the legs carrying preferably at their lower ends rollers or casters 16 to facilitate the shifting or moving of the machine when desired. At their upper ends, above the upper rails 12, a pair of channel beams 17 are supported in spaced relation preferably with the channel faces outwardly, and cross plates 18 are secured to the opposite ends of the channel rails which are provided with forwardly and upwardly disposed extensions 19 which are apertured to constitute bearing brackets within which the opposite ends of a shaft 20 is journaled for rotation. Adjacent one end the channel rails have secured to the upper side a fixed bearing member 21, while an adjustable bearing member 22 is mounted on the channel rail 17 adjacent the opposite end of the machine. The bearing members 21 and 22 are each of angle construction, including a horizontal flange 23 resting upon the upper flanges of the channel rails while the vertical flange 24 is formed with a substantially Y-shaped bearing 25. The rigid or immovable bearing member 21 has its horizontal flange 23 riveted or otherwise permanently secured as at 26 to the channel rail 17, while the horizontal flange 23 of the movable or adjustable bearing element 22 is provided with depending inwardly bent ears 27 which engage around the free edges of the upper flanges of the channel rail 17 whereby the bearing member 22 is mounted for longitudinal adjustments to relatively space the same from the rigid or immovable bearing member 21. A retaining bolt 28 is threaded through the horizontal flange of the movable bearing element for retaining the same in its longitudinally adjusted positions. The printing press rollers which consist of a central shaft A having reduced ends B constituting bearing trunnions are provided with a cylindrical body portion C which surrounds and is secured to the core or shaft A. As heretofore set forth the body portion C usually consists of a composition of glue and glycerine which provides a tough yieldable material having characteristics somewhat similar to rubber. The rollers in their original form as delivered have squared ends which are necessarily chamfered or trimmed off prior to their use. As heretofore explained, in the running of multi-colored work through a press, the surface of the roller is divided longitudinally into spaced sections by circumferentially grooving the roller body C. Under the present practice the ends are cut or trimmed by hand with a knife and the grooves are simultaneously formed by cutting parallel slits circumferentially, then gouging out the portion between the slits by hand with a knife. Due to the nature of the material from which the body C is made, the cutting requires a con-

siderable amount of time and labor and the grooves when completed in this manner are very rough and the edges of the grooves so uneven that pieces of the roller body pull away when running through the press which causes considerable damage both to the roller and to the work. The means which is employed in the present instance for trimming the ends of the rollers for forming peripheral grooves therein consists of tools 30 which comprise a tubular shank 31 carrying at one end a substantially gouge shaped cutting head 32 projecting from a casing 33 which houses an electric heating element 34 which when energized operates to heat the cutting head whereby the same will simultaneously cut and melt its way into the roller body. The free extremity of the cutting head is preferably inclined as at 34 and is formed at its juncture with the main portion of the head with an opening 35. Immediately in rear of the cutting edge 36 of the angularly disposed portion a smoothing, burnishing or healing bead 37 is formed on the under side thereof for a purpose to be hereinafter set forth. Preferably the cutting head 32 is detachably associated with the casing 33 so that heads of various shapes and sizes may be interchangeably associated with the casing. As illustrated the detachable association consists of a threaded shank 38 on the end of the casing and a threaded bore 39 in the cutting head. In order to provide means for mounting and associating the tools in operative relation to the roller when mounted in the machine, bearing elements 40 are provided which are in the nature of blocks having a bore 41 through which the shank 31 is axially movable. A set screw 42 intersects the bore 41 and is adapted to engage with the shank 31 for the purpose of retaining the shank and the tool in axially adjusted position and against rotation.

The lower portion of the bearing element 40 is provided with a bore or opening 43 extending therethrough at a right angle to the bore 41 and is of an appropriate size to snugly fit the shaft 20. A set screw 44 extends through the bearing element 40 and intersects the bore or opening 43 for retaining said bearing element in fixed position on the shaft 20 against axial or rotary movement with respect thereto. A longitudinal bar 45 is supported from one of the channel rails 17 by the uprights 46, the upper edge of said bar being substantially in the same plane with the axial center of the roller C when the said roller is supported by the bearing members 21 and 22. The bar 45 constitutes a tool rest upon which the free end of the casing 33 is designed to rest for holding the tool 30 in proper juxtaposition to the surface of the roller C. The heating elements 34 are connected to insulated con-

duits 47 which extend through the shank 31 and are provided at their free ends with plugs 48 adapted to be inserted in the sockets 49 which may be supported in turn from the upper side rail 12 of the framework of the machine and which sockets lead to a suitable source of supply 50 controlled by a switch 51.

In use and operation of the machine the roller trunnions B have placed over their opposite ends and in spaced relation thereto stop elements 52, after which the bearing member 22 is properly adjusted to mount the roller C in the bearings 25 for rotation. The tools 30 are then relatively spaced to cut the desired number of grooves and certain of the tools are adjusted for trimming the ends of the roller C. After the heating element has heated the cutting head to the desired temperature, the angularly disposed terminals are brought into proper cutting relation to the surface and ends of the roller C and the roller is manually turned in a direction toward the cutting edges as illustrated by the arrow in Fig. 6. The heated condition of the cutting edge combined with the sharp cutting edge 36 will serve to gouge out the surface of the roller C, the strip D which is cut therefrom feeding through the opening 35 whereby it is separated from the roller. The smoothing, burnishing or healing bead 37 which follows directly in rear of the cutting edge and which is also heated will serve to smooth off, burnish or heal the surface of the groove cut whereby a smooth finish is given to the walls of the groove. Simultaneously with the formation of the grooves, it will be understood that the ends will be trimmed so that when the roller has been completely rotated in the presence of the tools, the trimming and grooving is completed in a single operation. Where it is desired to cut a spiral or helical groove in the feeding roller for the purpose of reducing the surface thereof, one or more of the tools may be employed. For this purpose it will be noted that the shaft 20 is provided with a spiral groove or thread 52 running throughout its length, while the bearing element 20 is provided with a laterally projecting lug 53 immediately above the opening or bore 43. The lug is provided with an elongated slot 54. A key 55 is carried by the lug and the same is provided with an enlarged medial boss 56 conforming approximately to the shape of the slot 54. Normally the key is retained in an elevated position, as illustrated in Fig. 4, by the arrangement of the boss 56 crosswise of the opening 54 and resting upon the lug 53. When, however, the spiral cutting or grooving is to be accomplished, the key is turned to permit the boss 56 to register with the slot 54 whereby the boss will move therethrough to lower the key until its lower end engages in the

spiral groove or thread 52 in the shaft 20. The key is then rotated until the boss 56 lies crosswise beneath the lug 53. The set screw 44 in this use of the machine is loosened whereby the complete tool 30 and its bearing member 40 is free to be moved longitudinally or axially by the rotation of the shaft 20. A crank handle 57 is attached to one end of the shaft 20 for this purpose. In this use of the machine a sprocket 58 is secured to the end of one of the reduced portions or trunnions B and is coupled by means of a sprocket chain 59 to a sprocket 60 secured to the end of the shaft 20 opposite to that which carries the crank handle 57. By manipulating the crank handle 57 the heated cutting head 32 will be simultaneously fed lengthwise of the roller C, while the roller C is rotating in a direction toward the cutting head. This will effect the cutting of the spiral groove for reducing the surface area of the roller for the purpose heretofore set forth. By loosening the set screw 42 it is, of course, obvious that the cutting heads 32 may be moved toward or away from the surface of the roller to regulate the depth of the groove to be cut, as well as its width. It is of course to be understood that where a straight groove is to be cut the sprockets 58 and 60 and sprocket chain connecting the shaft 20 and the roller C are not employed and are removed when the machine is used in this capacity.

I claim:

1. A machine for trimming the ends and grooving the surface of printing press rollers, comprising means for supporting said rollers for rotation, a cutting tool, means for supporting the effective portion of the cutting tool in operative relation to the path of movement of the surface of the rollers to be cut, and means for heating the effective portion of the tool.

2. A grooving and trimming machine for printing press rollers comprising a supporting frame, relatively adjustable bearing members for supporting a roller for rotation on the frame, a rotary shaft mounted in the frame parallel to the axis of the roller, a plurality of cutting tools, tool carriers in which the tools are mounted for longitudinal adjustments toward and away from the roller, said tool carriers mounted on the rotary shaft for adjustments longitudinally of the roller, means for retaining the tools in their adjusted positions in the carriers, means for retaining the carriers in adjusted positions on the shaft, and means for heating the cutting edges of the tools.

3. A grooving machine for printing press rollers comprising a supporting frame, relatively adjustable bearing members for supporting a roller for rotation on the frame, a rotary shaft mounted in the frame parallel to the axis of the roller, a plurality of cut-

ting tools, tool carriers in which the tools are mounted for longitudinal adjustments toward and away from the roller, said tool carriers mounted on the rotary shaft for 5 adjustments longitudinally of the roller, means for retaining the tools in their adjusted positions in the carriers, means for retaining the carriers in adjusted positions on the shaft, means for heating the cutting 10 edges of the tools, the said rotary shaft having a spiral peripheral groove, means on the tool carriers for engagement with the

groove, and means for coupling the roller and said shaft for simultaneous movement whereby spiral grooving of the roller surface 15 may be effected by the machine.

4. In a device of the character described, a cutting tool having a sharp cutting edge, a bead formed on the tool beneath the cutting edge so as to engage with the work 20 subsequent to the engagement of the cutting edge therewith, and means for heating the tool including the cutting edge and the bead.

CLAUDE MILTON EARLEY.
